(57) **CLAIM**

The ornamental design for a display of mobile phone with transitional graphical user interface, as shown and described.

DESCRIPTION

FIG. 1 is a front view of a first image in a sequence for a display of mobile phone with transitional graphical user interface.

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof; and,

FIG. 12 is a front view of a twelfth image.

The appearance of the transitional image sequentially transitions between the images shown in FIGS. 1-12. The process or period in which one image transitions to another image forms no part of the claimed design.

The broken line showings of the display, mobile phone, and portions of the graphical user interface are included for the purpose of illustrating environmental structure and form no part of the claimed design.
